DESIGN FOR A BUTTON

Leonard R. Carley, Watertown, Conn., assignor to
The Patent Button Company, Waterbury,
Conn., a corporation of Connecticut

Application October 10, 1935, Serial No. 58,936

Term of patent 14 years

To all whom it may concern:

Be it known that I, Leonard R. Carley, a citizen of the United States, residing at Watertown, in the county of Litchfield and State of Connecticut, have invented a new, original, and ornamental Design for Buttons, of which the following is a specification, reference being had to the accompanying drawing, forming part thereof, in which:

Fig. 1 is a top plan view of a button on an enlarged scale showing my new design; and

Fig. 2 is an edge view thereof, a portion of the cap of the button being in transverse section, said section being taken on the line 2—2 of Fig. 1.

I claim:

The ornamental design for a button as shown.

LEONARD R. CARLEY.
